UNITED STATES PATENT OFFICE.

ADOLPH BEHN AND JOHN GUSTAV SCHMITT, OF BROOKLYN, NEW YORK.

INTERNAL-COMBUSTION MOTOR.

1,423,073.

Specification of Letters Patent. Patented July 18, 1922.

Application filed August 12, 1920. Serial No. 403,023.

To all whom it may concern:

Be it known that we, ADOLPH BEHN and JOHN GUSTAV SCHMITT, citizens, respectively, of the United States and of the Republic of France, residing at Brooklyn, in the county of Kings and State of New York, have invented certain new and useful Improvements in Internal-Combustion Motors, of which the following is a specification.

Our invention relates to internal combustion motors and more particularly to high powered motors of the multi-cylinder four stroke cycle type.

In the design of gasoline motors for driving automotive vehicles, four things are especially important: First, it is important to secure maximum power for a given weight and predetermined piston displacement; second, it is important to provide for continuous operation, at full speed, if necessary, for periods of long duration and with the least possible wear and tear on the working or moving parts of the motor; third, it is important to secure maximum power output with a minimum of fuel consumption; and fourth, it is important to so arrange the working pistons, the crank-shaft and connecting rods, in a four stroke cycle motor, that the driving power, generated through the successive explosions in the motor cylinders, is transmitted evenly and uniformly to the crank-shaft and with the least possible vibration. In the design and development of our motor, these fundamental pre-requisites have at all times been borne in mind.

The motor of our invention is principally characterized by the provision of two working pistons for each of the motor cylinders, the pistons of each cylinder at all times moving oppositely—i. e., alternately toward and away from each other; the explosion of the combustible gases, between the opposed cylinders, driving the pistons apart. Broadly, such a piston arrangement is old. Prior explosion motors, however, in so far as we are aware, if practical, have included but a single cylinder, and in each instance have operated on the two stroke cycle principle. Accordingly, it is an object of the present invention to de-

vise a four stroke cycle, multi-cylinder motor, in which two working pistons for each motor cylinder are provided (instead of one as heretofore). Through such an arrangement the power output of the motor for a given piston displacement is materially increased, fuel consumption minimized, weight decreased, vibration lessened, compression augmented, production cost reduced, suction increased, and a uniform power transmission between the working pistons and the crank-shaft of the motor obtained. A motor having a higher all around efficiency is the result.

A further characteristic of the invention is the grouping of the cylinders in blocks of two each and the provision of a single counter-shaft for each cylinder block. In the embodiment of our invention selected for illustration a four cylinder, vertical cylinder motor is shown. The counter-shafts, one for each cylinder group, are mounted overhead and are connected with the upper pistons of the several cylinders and with the crank-shaft. The crank-shaft is contained in the crank-case and is directly connected with the lower pistons of the several cylinders by ordinary connecting-rods. The counter-shafts are movable bodily with the upper pistons, and since they are also directly connected with the crank-shaft, obviously the latter receives a doubly strong power impulse with each working or power stroke. The motor, in this regard, may be compared to a steam engine in that the power-shaft or crank-shaft is simultaneously "pushed" and "pulled."

The invention is further characterized by improvements in structural details. Among other things we have devised, what will be hereinafter designated, demountable or removable counter-shaft guides. Each guide includes a pair of guide plates having opposed parallel vertical grooves between which ball-faced bearing members, carried by the counter-shafts, are fitted. These ball members or bearings reciprocate between the guide plates and at all times firmly though movably hold the counter-shafts in place. Preferably, two bearing members are provided for each cylinder.

Still another characteristic of the invention is the grouping of the cylinders in a manner such that the pistons of adjacent cylinders (the cylinders cast en bloc) will move simultaneously and alike, i. e., will execute simultaneously on the one hand the power stroke and the intake stroke, and on the other hand, the compression stroke and the exhaust stroke, or vice versa, thereby necessitating the use of but a single overhead counter-shaft for each cylinder group. Were the firing order otherwise, individual counter-shafts for the individual cylinders would be required.

It will be further noted hereinafter that still other improvements and refinements in details of construction and arrangement of parts exist. The valve chambers or valve castings, like the overhead counter-shaft guides, are made demountable and are preferably fastened to the cylinder blocks intermediate of the cylinder ends. But one set of valves is provided for each cylinder and the valve chamber castings, of which there are two, are fashioned to accommodate four valves each (two intake and two exhaust) and to span the cylinders constituting a single group. For cooling, the valve chambers are water jacketed, the valve chamber jackets and the water jackets provided for the motor cylinders being in communication. Valve operating mechanism of more or less conventional design is used and operated from a cam-shaft contained in the crank-case and geared to the crank-shaft; the gear ratio being two to one. The manner in which the water-pump, generator, magneto, and other motor accessories are mounted and arranged will be fully hereinafter explained.

It is sufficient to emphasize at this time that the motor in its entirety is notably free from intricacies of mechanical detail, strong, light in proportion to horse-power developed, reliable, and so organized and arranged as to render all parts readily accessible for repair or replacement purposes.

In the drawings, wherein the various structural details of the motor are fully illustrated, and wherein like reference characters denote like or corresponding parts,

Fig. 1 is a side elevation of our improved four stroke cycle multi-cylinder motor,

Fig. 2 is a top plan view,

Fig. 3 is a longitudinal vertical sectional view,

Fig. 4 is a transverse vertical sectional view showing the cam-shaft gearing and jack-shaft drive,

Fig. 5 is a transverse vertical sectional view through one of the passageways formed in the cylinder castings between the cylinders constituting a cylinder group,

Fig. 6 is a detail longitudinal vertical sectional view, partly in elevation, of one of the cylinder groups showing the counter-

shaft construction and its relation to the vertical guides,

Fig. 7 is a detail plan view of a portion of one of the cylinder groups,

Fig. 8 is a detail perspective view of one of the counter-shaft guides,

Fig. 9 is a detail longitudinal vertical sectional view of one of the motor cylinders showing the relation of the valves (intake and exhaust) thereto, and

Fig. 10 is a section on the line 10—10 of Fig. 9.

In the embodiment of the invention herein illustrated, a four cylinder, vertical cylinder motor is shown. Obviously the number of cylinders may be varied, and if desired, the cylinders may be arranged horizontally or otherwise. The crank-case of the motor comprises an upper crank-case section 10, a lower crank-case section 11, integral main crank-shaft bearings 12 (three in number), lateral arms or bearers 13 (four in number), and an integrally formed enlargement 14 having provision thereon in the form of a lug 15 for centering the motor on the chassis (not shown) of an automobile or other automotive vehicle. The crank-shaft 16 of the motor extends throughout the full length of the crank-case and at its forward end is equipped with suitable clutch mechanism 17 for cranking or starting and at its rear end (without the crank-case) with a fly-wheel 18, the purpose of which is obvious. The crank-case sections 10 and 11 are bolted together as indicated at 19 and the lateral arms or bearers 13 of the crank case are arranged two on either side, to rest upon the motor support. The main bearings 12 are spaced equi-distantly and extend transversely of the upper crank-case section 10. Preferably the bearings 12 are flanged or ribbed for increased strength and divided; the bearing sections being bolted together as indicated at 20.

The number of cylinders shown is four. Beginning at the forward end of the motor, the cylinders are numbered respectively 21, 22, 23 and 24; the cylinders 21 and 22 constituting one group or cylinder block and the cylinders 23 and 24 the other. When the number of cylinders is increased to more than four (eight for instance), they, the cylinders, may be grouped four to a group or cylinder block or, if desired, two to a group as shown. In either construction the cylinders are supported directly upon and fastened to the upper crank-case section 10 coincident with openings 25 formed in the crank-case. For convenience in assembly the cylinder groups are made removable.

Each cylinder block or group comprises an integral casting having a central vertical bore or passageway 26 formed in it between the cylinders. The cylinders and

the passageways 26 are both, or rather all, open ended and the passageways are in registry with openings 27 formed in the crank-case section 10. Within the bearings 5 or passageways 26 connecting rods 28 operate.

As explained hereinbefore, each cylinder is provided with two working pistons. The pistons of each cylinder are designated as 10 29 and 30; 29 designating the lower pistons and 30 the upper pistons of the several cylinders. The provision of two pistons per cylinder, in a four cylinder motor, puts the total number of pistons at eight, i. e., a 15 number corresponding to the number ordinarily provided in an eight cylinder motor of conventional design. The pistons 29 and 30, however, considered collectively, do not, as in the ordinary motor, operate, one at 20 a time, in a predetermined firing order. Contradistinctively the pistons operate in pairs, the pistons of one cylinder acting oppositely and at all times moving either toward or away from each other. In this 25 manner the explosion charge admitted to the combustion chambers of the several cylinders, when compressed and ignited, drives the pistons apart; directly imparting to both pistons of each cylinder a power 30 impulse which is transmitted to the crank-shaft—from the lower pistons directly and from the upper pistons indirectly. Accordingly, the power output of the motor per cylinder, and for a given piston dis- 35 placement, as well as for a given amount of fuel, is appreciably increased, and a larger percentage of the total number of heat units available converted into energy and utilized. Moreover, the piston stroke 40 is shortened, compression augmented and induction due to suction intensified.

Mechanically, the pistons 29 and 30 are quite similar in construction and design to the pistons of the ordinary one-piston-per 45 cylinder motor. Each is provided with an appropriate number of piston rings 31 and each receives its power impulse through the explosion of an ignited fuel charge.

The valve mechanism for controlling the 50 intake and exhaust of the fuel charge and burnt gases respectively comprises an intake valve 32 and an exhaust valve 33 for each motor cylinder. Preferably the valves 32 and 33 are contained in a divided valve 55 casting 34 of a construction adapting a single casting to receive the separate valves for the cylinders of a group. The castings 34 are bolted or otherwise removably fastened as indicated at 35 to the cylinder 60 groups or blocks, and as illustrated in Figs. 1 and 9, are positioned intermediately of the ends of the cylinders rather than at one end thereof as heretofore. The valves 32 and 33 are each confined to suitable valve 65 chambers, an individual valve chamber be-

ing provided for each of the several valves. In the interest of simplicity however, the individual valve chambers are open to the cylinders by way of combined intake and exhaust ports 35'; but a single port being 70 thus required from each motor cylinder. Moreover, instead of providing a number of intake and exhaust valves in direct proportion to the number of pistons actuated on by an ignited charge the number required is 75 herein reduced by half, a characteristic tending to minimize weight and cut production cost to a minimum.

The valve operating mechanism is directly 80 acted upon by cams 36 mounted on the cam-shaft 37 of the motor. The cam-shaft is in parallelism with and is mounted in suitable bearings 37' inside the crank-case, an enlargement of the crank-case denoted 38, being provided for this purpose. Cam-fol- 85 lowers 39 extend into the crank-case enlargement 38 in axial continuation of a corresponding number of push rods 40. The inner or enclosed ends of the cam-followers are provided with enlarged bearing surfaces 90 41 which bear directly on the cams 36. The outer ends of the cam-followers, on the ends which bear directly against the push rods, though somewhat similarly enlarged as at 42, are nevertheless made adjustable in order 95 that the space between the cam-followers and push rods may be varied. Lock-nuts 43 prevent movement of the adjustable bearing surfaces 42 subsequent to adjustment.

The push rods 40, which are nothing more 100 nor less than attenuated valve stems, reciprocate in direct proportion to the rotating speed of the cam-shaft. For every revolution of the cam-shaft the push rods are actuated once, such actuation being directly 105 against the tension of springs 44 which encircle the push rods and bear respectively against discs 45 adjustable on the rods and the under walls of the valve castings 34. These springs 44 tend to urge the valves 32 110 and 33 at all times into seating engagement and 33 at all times into seating engagement with their respective valve seats. Meshing gears 45' and 46, having a gear ratio of two to one, drive the cam-shaft from the crank-shaft thus imparting to the former one complete revolution for every two complete revolutions of the crank-shaft.

In a four cylinder motor of the type disclosed, fourteen connecting-rods are used. The lower pistons 29 of each cylinder are 120 directly connected with the crank-shaft by connecting-rods 47. In this way the power impulses applied to the pistons 29 are transmitted directly to the crank-shaft. The upper pistons 30, as distinguished from the lower pistons 29, are directly connected with overhead counter-shafts 48 by connecting-rods 49. Accordingly, the power impulses applied to the upper pistons 30 are directly transmitted to the counter-shafts. The 130

counter-shafts 48, of which there are two, one for each cylinder group, are mounted directly over the upper cylinder ends, and are bodily removable with the pistons 30. From the 5 counter-shafts, power is transmitted to the crank-shaft by the connecting-rods 28 and connecting-rods 49', the connecting-rods 28, as hereinbefore pointed out, being extended through the passageways 26 formed in the 10 cylinder blocks or castings. The connecting rods 49' are preferably arranged at opposite ends of the cylinder castings and with the connecting-rods 28 are so related to the connecting rods 47 as to exert on the crank-shaft 16 a "pull" in contra-distinction to the 15 "push" applied to the crank-shaft by the connecting rods 47.

For each group of cylinders the crank-shaft is off-set laterally at five different 20 points making the total number of off-sets in the crank-shaft, ten. The offsets in the crank-shaft are alternately oppositely extended, the corresponding off-sets being respectively provided, on the one hand for the 25 two connecting rods 47, and on the other hand for the three connecting-rods 28 and 49' of the cylinder group. The former of these connecting-rods (47) "push" the crank-shaft in driving it, whereas the latter (28 30 and 49') simultaneously "pull" the crank-shaft; such simultaneous "push" and "pull" as before explained, being conducive to smoothness of operation, an increase in power, and a marked decrease in motor vibration at all operating speeds.

The counter-shafts 48 are held in place by opposed vertical guide plates 50. The guide plates 50, of which there are four (two for each cylinder group) are removably fastened 40 directly to the cylinder castings. Each plate (see Figs. 7 and 8) is longitudinally grooved as indicated at 50', the grooves of all plates being parallel. Bearings 51, in the nature of ball bearings, are fitted on the counter-shafts and are held in place by set screws 52. Preferably the bearings are positioned on the counter-shafts between the connecting rods 28, 48 and 49' and are confined to the space defined by the guide plate grooves. 45 Thus positioned, the counter-shafts are free to rotate and bodily reciprocate though firmly held against lateral displacement by the guide plates 50. For lightness and convenience in assembly, the counter-shafts are hollow and are provided with end-caps 53 held over the shaft ends by rods 54' extended through the end caps and the hollow counter-shafts as well.

In order that a single counter-shaft 48 60 may suffice for two cylinders, it is essential that the firing order of the several cylinders bear a certain definite relation to each other. As herein shown, the firing order is 2—4—1—3, the cylinders being numbered 1—2—65 3—4 consecutively beginning with 1 at the

forward end of the motor. With the firing order thus, the pistons of adjacent cylinders or of separate cylinder groups at all times move in unison, i. e., the pistons of one of the cylinders of one group execute their power 70 stroke simultaneously with the execution of the intake stroke of the pistons of the other cylinder and, conversely, the pistons of one of the cylinders of the other group execute their compression stroke simultaneously 75 with the execution of the exhaust stroke of the pistons of the remaining cylinder, or vice-versa. Through such an arrangement only is it possible to link up adjacent cylinders by the use of a counter-shaft common to 80 both or all of the cylinders of a group.

For cooling the motor during its operation the cylinders are jacketed as at 75 and the valve castings 36 are similarly jacketed as at 76, the jackets 75 and 76 being in communication (see Fig. 10). The water or other cooling medium contained in the jackets 75 and 76 is continuously circulated by a water circulating pump 77 interpolated in the connection 78 between the bottom end of 90 the radiator 79 and a water manifold pipe 80 extended transversely across the bottom ends of the several cylinder water jackets. A second water manifold pipe 81, extended across the tops of the water jackets, and a connection 82 between the manifold pipe 81 and the top of the radiator, completes the water circuit. The pump 88, together with a magneto 83 and generator 84 is driven by a jack-shaft 85 in turn driven from the 100 crank-shaft 16. The driving means for the jack-shaft 85 is illustrated in Fig. 4 and comprises sprockets 86 and 87 and a chain 88. Preferably, the jack-shaft is in parallelism with the crank-shaft though extended 105 without the crank-case on the side of the motor opposite to the cam-shaft 37. The carburetor or carburetors used (not shown) may be of any well known construction.

From the foregoing it will be noted that 110 an increased power output per cylinder is attained, due to the piston arrangement; that vibration ordinarily quite noticeable in multicylinder four stroke cycle motors is minimized due to the "push" and "pull" action of the crank-shaft; that production cost is lowered due to the extreme simplicity of construction; that the weight of the motor is reduced due to its compactness and to the absence of a duplication of parts; and that 115 fuel consumption for a given power output is very materially reduced, due principally to the fact that each explosion drives two pistons rather than one as heretofore. Furthermore, such improved constructional details and refinements as have been pointed out hereinbefore lend greatly to the desirability of the motor; especially the grouping of the cylinders in pairs and the arrangement of the counter-shafts and con- 120 125 130

necting-rods in a manner such that individual counter-shafts serve the several cylinders of a cylinder group.

While we have described our invention in detail in its present preferred embodiment, it will be obvious to those skilled in the art after understanding our invention, that various changes and modifications may be made therein without departing from the spirit or scope thereof. We aim in the appended claims to cover all such modifications and changes.

What is claimed is:

1. In an internal combustion motor, a cylinder, a piston, a reciprocable counter-shaft, a connection between the piston and counter-shaft, opposed guides for the counter-shaft, each guide including a grooved bearing surface, a bearing member carried by the counter-shaft to fit between and with the grooves of the opposed guides, a crank-shaft, and a connection between the counter-shaft and the crank-shaft.

2. In an internal combustion motor, a cylinder, a piston, a bodily reciprocable counter-shaft, a connection between the piston and counter-shaft, guides for the counter-shaft including plates having parallel grooves formed therein, a bearing member carried by the counter-shaft to fit between the grooves of the opposed plates, a crank-shaft, and a connection between the counter-shaft and the crank-shaft.

3. In an internal combustion motor, a plurality of cylinders, two pistons for each cylinder, the pistons of each cylinder being arranged to alternately move toward and away from each other, a counter-shaft, a guide for the counter-shaft including opposed guide plates having parallel grooves, a bearing member carried by the counter-shaft to operate between the plates within the grooves, a connection between one of the pistons of each cylinder and the counter-shaft, a connection between the other of the pistons of each cylinder and the crank-shaft, and a connection between the counter-shaft and crank-shaft.

4. In an internal combustion motor, a plurality of cylinders arranged in groups of two or more cylinders each, cylinder water jackets common to the cylinders of each group, two pistons for each cylinder, the pistons of each cylinder being arranged to alternately move toward and away from each other and to define a combustion chamber intermediately of the ends of the cylinders, valve mechanism including an intake valve and an exhaust valve for each cylinder, the valves for the cylinders of each group being enclosed in removable valve casings common to the cylinders of such group, the valve casings in each instance being situated directly opposite the explosion chambers formed in the several cylinders, valve casing water jackets for the separate valve casings, the valve casing water jackets and the cylinder water jackets being in communication, a crank-shaft, a direct connection between one of the pistons of each cylinder and the crank shaft, a separate indirect connection between the other of the pistons of each cylinder and the crank shaft, and valve operating mechanism for the valves.

water jackets for the separate valve casings, the valve casing water jackets and the cylinder water jackets being in communication, a crank-shaft, a direct connection between one of the pistons of each cylinder and the crank shaft, a separate indirect connection between the other of the pistons of each cylinder and the crank shaft, and valve operating mechanism for the valves.

5. In an internal combustion motor, a plurality of cylinders arranged in groups of two each, the cylinder water jackets common to the cylinders of each group, two pistons for each cylinder, the pistons of each cylinder being arranged to alternately move toward and away from each other and to define a combustion chamber intermediately of the ends of the cylinders, valve mechanism including an intake valve and an exhaust valve for each cylinder, the valves for the cylinders of a group being enclosed in removable valve casings common to the cylinders of such group, the valve casings in each instance being situated directly opposite the explosion chambers formed in the several cylinders, valve casing water jackets for the separate valve casings, the valve casing water jackets and the cylinder water jackets being in communication, a crank-shaft, a direct connection between one of the pistons of each cylinder and the crank-shaft, a separate indirect connection between the other of the pistons of each cylinder and the crank-shaft, the arrangement of the connections being such for each two cylinders three connections are provided, and valve operating mechanism for the valves.

6. In an internal combustion motor, two cylinders, two pistons for each cylinder, a crank shaft, a counter shaft, a direct connection between the crank shaft and one of the pistons of each cylinder, a direct connection between the counter shaft and the other piston of each cylinder, opposed guide plates arranged on opposite sides of the counter shaft to guide it in its reciprocable movement, a connection between the counter shaft and the crank shaft, and a ball-end formed on the connection last mentioned to reciprocate with the counter shaft between grooves formed in the guide plates.

7. In an internal combustion engine, a plurality of cylinders, two pistons for each cylinder, a crank-shaft, an overhead hollow reciprocating counter-shaft, a direct connection between the crank-shaft and one of the pistons of each cylinder, a direct connection between the counter-shaft and the other piston of each cylinder, direct connections between the hollow counter-shaft and the crank-shaft, guides for the hollow counter-shaft, and caps at the ends of the hollow counter-shaft, each cap being extended into the hollow end thereof.

8. In an internal combustion engine, a

cylinder, a piston, an overhead counter-shaft reciprocable with the piston, a crankshaft, a rigid connection between the counter-shaft and crank-shaft, grooved guides for the counter-shaft erected upon the cylinder, and a ball member carried by the counter-shaft to operate within the grooves of the guides,

the ball member being adjustable axially of the counter-shaft.

In testimony whereof we hereunto affix 10 our signatures.

ADOLPH BEHN.

JOHN GUSTAV SCHMITT.
